UNITED STATES PATENT OFFICE.

GEORG FRIEDRICH LEBIODA, OF BOULOGNE-SUR-SEINE, FRANCE.

APPARATUS FOR IMPREGNATING WOOD.

SPECIFICATION forming part of Letters Patent No. 655,788, dated August 14, 1900.

Application filed March 31, 1900. Serial No. 10,977. (No model.)

To all whom it may concern:

Be it known that I, GEORG FRIEDRICH LEBIODA, a subject of the King of Prussia, German Emperor, residing at the city of Boulogne-sur-Seine, in the Republic of France, have invented certain new and useful Improvements in Apparatus for Impregnating Wood, of which the following is a full, clear, and exact description.

10 This invention relates to an apparatus for impregnating tree-trunks and timber longitudinally in a constant current.

The improvement consists in a container or vessel being provided at one end with a 15 door or cover which is fitted with a number of pipes extending into bell-mouthed cutters and at its other end closed by a cover having special partitions in such a way that a corresponding number of tubes fitted with pistons 20 and also extended into bell-mouthed cutters may be moved forward under the action of a pressure medium in either direction and also serve for injecting or withdrawing the impregnating liquid. For this object the 25 partitions and the cover at one end of the container or receiver are arranged to form three different chambers, the outer one of which serves for injecting the impregnating liquid into the wood, the middle one for producing the movement of the pistons in one 30 direction, and the inner one for producing the movement of the pistons in the other direction. At the other end the cover, which is preferably suspended on a hinge and fastened by screw-bolts, forms in common with 35 an inserted wall or partition a chamber which allows the impregnating liquid to be conveyed through the wood from this end also and after the bell-mouthed cutters have been released 40 at the other end by the use of the pressure medium effects the release of the completely-treated wood from the bell-shaped cutters provided at this end.

The following may be employed as impregnating mediums: first, cold or warm water, either pure or mixed with suitable additions in order to expel natural sap from the wood and to ripen the latter; second, dyes of suitable composition for artificially coloring the 45 wood; third, antiseptic or the like substances which render harmless substances liable to ferment in the wood, and thus prevent decomposition and protect the wood against the attacks of grubs and insects;

fourth, fireproof substances for protecting 55 the wood against destruction by conflagration, and, fifth, other suitable liquids or gaseous substances which are suitable for treating tree-trunks and longitudinal wood.

The invention will now be described with 60 reference to the accompanying drawings, in which—

Figure 1 is a longitudinal section of the improved apparatus; Fig. 2, an end view; Fig. 3, a vertical section on the line A B of 65 Fig. 1; Fig. 4, a vertical section on the line C D of Fig. 1. Fig. 5 is a view of a detail.

The apparatus is composed of a cylinder or other suitable receiver *a*, which may rest in a horizontal position on a suitable frame 70 or support. The cylinder *a* is provided at both ends with annular flanges for securing the covers or doors *g* and *l*. A steam-coil *b* is arranged in the interior of the cylinder, which coil allows of the liquid contained in the interior of the vessel being heated. Two rails or bars *c* for the rollers *d* of the carriage *e*, containing the wood, are provided in the interior of the vessel. The cover or door *l* is connected with the cylinder *a* by means of a 75 hinge *h* and may be firmly connected with the annular flange of the vessel *a* by means of three screw-bolts *i*, while india-rubber gaskets *k* or metal or other suitable washers may also be employed for insuring a 80 hermetic closing of the joint.

The door or cover *g* in the present example of construction is attached to the vessel *a* by means of long screw-bolts *m*, three partitions *j o s* being inserted between the door 90 and the vessel. After the screw-bolts *m* have been suitably tightened up an air-tight joint is secured by means of the flange *n*. The cover *g* forms, with the three internal partitions *j o s*, three inner chambers *p q r*. The 95 partitions *j o s* are perforated, in the example shown, at twelve places. In each of these perforated places a pipe *t* is adjustably mounted, which extends from the chamber *p* into the vessel *a*. The end of the pipe *t* toward the chamber *p* is free, while the other end, toward the vessel *a*, extends into a bell-mouthed cutter, which can penetrate into the end faces of the wood to be treated.

Lining pieces or bushes *v* are inserted in 105 openings in the partition *j*, which bushes in turn allow passage to the pipes *t*. Stuffing-boxes *w* are inserted in the bushes *v* on the

side of the partition facing the chamber *p*, which stuffing-boxes or glands may be held immovably by screw-nuts *x*, which are tightened up, and thus the thorough tight jointing of the pipes *t* from the chamber *p* toward the partition *j* is rendered possible. The ends of the pipes *t* are fitted tightly from the cylinder *a* in a similar manner in the partition *s* by means of stuffing-boxes or glands *o* directly let in the partition.

Each perforation of the central partition *o* is formed as a cylinder, in which a piston attached to the pipe *t* is movable. This piston consists of a disk *y*, which is engaged on both sides by leather washer-rings *z*. On each of these rings *z* a metal disk is placed, and the different parts are combined to a solid whole by means of nuts *l*, mounted on the pipes *t*. (See Fig. 5.)

Each of the chambers *p q r* is provided with a tap—that is, the chamber *p* with a tap *2*, the chamber *q* with a tap *3*, and the chamber *r* with a tap *4*. These taps may, according to requirements, be utilized sometimes for the admission and sometimes for the discharge of the impregnating liquid or suitable medium of pressure. The cover or door *l* is also provided with a chamber *5*, attached to the container. In the wall of this chamber, facing the container, there are mounted twelve pipes extending into bell-mouthed cutters *6*, which are in communication with the chamber *5*. The cutters of these pipes stand directly opposite the cutters of the other tubes at the other end.

Instead of the number of pistons or perforations shown of course other proportions may be chosen, according to requirements and according to the number and diameter of the pieces of wood to be treated. It is also easy to stop up one or other of the pipes when it is desired to put it out of action. Further, a tap *7* is provided on the door or cover *l*, which tap is in communication with the chamber *5* and serves sometimes for admitting the impregnating liquid into the container and sometimes for discharging the same. The container *a* has on its periphery a manometer *8*, an air-cock *9*, a cock *10* for attaching thereto the high-pressure pump, and a tap *11* for the inlet and outlet of the impregnating liquid. A pipe *12* serves for the admission of steam into the steam-coil *b* and a pipe *13* for the discharge of the said steam.

The pieces of wood to be treated are preferably arranged in a frame wagon in the manner shown in Figs. 1 and 4, the compartments of which wagon may exactly correspond to the arrangement and number of the pistons; but it is equally easy to adjust all the pistons on a single trunk when the latter fills up the diameter of the injecting apparatus. Also several pistons may be adjusted on one trunk, and trunks of different diameters may be treated at once so long as the frame wagon is suitably arranged.

The operation and mode of working of the apparatus hereinbefore described are as follows: The three screws *i* of the cover or door *l* are unfastened and the latter is opened. The frame wagon loaded with wood is then inserted, which wagon rests on a suitable support and is run into the opened apparatus until the ends of the pieces of timber encounter the cutters. The door *l* is then closed and again made fast by means of the bolts *i* on the apparatus. All taps are then closed except the tap *3*, through which impregnating liquid is admitted into the chamber *q* by means of a force-pump. A manometer arranged on the said pump soon shows whether the liquid in the chamber *q* is under pressure. As soon as it has commenced to work the liquid will force the pistons and the pipes *t*, connected with them, toward the interior of the vessel *a*, and this movement will continue until the cutters *u* and also the cutters *6* of the cover *l* have penetrated sufficiently deep into the wood, whereupon the cutters are securely tight-washed toward the wood. The automatic independent operation of each piston allows pieces of wood of different lengths to be impregnated simultaneously. The tap *3* is then closed, the high pressure in the chamber *q* remaining unweakened. The tap *11* is then opened and the vessel *a* is filled with impregnating liquid, the air-tap *9* being opened to allow of the vessel being more easily filled and again closed when it is filled. The tap *2* is then opened and liquid is allowed to penetrate into the chamber *p* by the action of the high-pressure pump, the liquid soon passing through the pipes *t* and under the increasing pressure through the tight-fitting cutters *u* penetrating into the wood and traversing the latter through its entire length in order to pour into the chamber *5* through the pipes provided with cutters *6*. The precaution is then adopted of opening the tap *7* in order to allow the liquid accumulating in the chamber *5* to be discharged. Preferably this discharge from the tap *7* is returned by the pump to the impregnating substances and in the course of the operation is again pumped into the cylinders.

In the course of treating a series of long timbers or tree-trunks it is preferable to change the direction of the impregnating fluid. Where dyes are used, this is absolutely necessary, because one end of the trunk might easily be more highly colored than the other. The change of direction is also advisable even during the impregnation, because the respective operations proceed very rapidly, and the impregnation is much more regular when there is such a change of direction. For this object the pressure of the pump is shut off from the chamber *p* and the liquid is allowed to run out of this chamber, the tap *2* being left open. The chamber *q* remains always under pressure with the tap *3* shut. The pressure-pump is then caused to force the

liquid through the tap 7 into the chamber 5, from whence it penetrates the wood through the bell-mouthing cutters 6, and after passing through the entire length of the wood finally reaches the chamber *p* through the pipes *t*. From the chamber *p* it runs away through the tap 2, which has remained open and can be again charged with the impregnating substances. After this treatment the wood is thoroughly and reliably impregnated in all its parts. During the treatment the manometer 8 has indicated the average pressure ruling in the cylinder, while a safety-valve arranged on the pressure-pump has provided that the high pressure employed shall not exceed the power of resistance of the apparatus. The steam-coil *b* has maintained the liquid during the impregnation at the desired temperature. A device may be arranged on the outer pipe connection, which device maintains automatically the heat to the desired degree.

Before the completely-treated wood is removed from the apparatus it is necessary to again release the cutters *u* and 6, which have penetrated into the wood. In order to allow of this being done, the taps 11, 3, and 7 and the air-tap 9 are opened, whereby the cylinder *a* and the chambers *q* and 5 are freed from pressure and from the liquid. The liquid under pressure is then allowed to enter the chamber *r*, the tap 4 being opened, by which means the pistons very soon force the pipes *t* toward the chamber *p*, causing the release of the cutters *u* and their entire withdrawal from the ends of the wood. Pressure is then shut off the chamber *r* and the liquid is allowed to run out of the same. The liquid under pressure is then conveyed to the chamber 5 and penetrating through the pipes and cutters 6 releases the wood from the said cutters, because the wood is now free and without support at the other end. In consequence of this last manipulation the wood is now free at both ends, so that after the door *l* has been opened the frame wagon can be removed from the apparatus, and then after the injecting apparatus has received a fresh charge the operation hereinbefore described may be repeated.

The method hereinbefore described of impregnating wood allows of a complete and extremely-rapid treatment of the hardest and greenest or freshest wood of very large diameter. The impregnation also takes place in a constant current, and the liquid is forced to take its flow through the wood in the direction of its fibers. Consequently the necessary quantity of impregnating substances may be deposited in the wood.

The great advantages which this improved apparatus affords over all hitherto employed are as follows:

First. The wood is not merely impregnated on its periphery, but the heart or core of the wood is also impregnated.

Second. It is possible to treat whole trunks of the largest diameter and of any length.

Third. The impregnation of the wood can take place whether the latter be in a green or seasoned condition.

Fourth. The impregnation takes place with extraordinary rapidity, although the apparatus may appear somewhat complicated in its construction and operation. In a few hours freshly-felled very hard tree-trunks—such, for instance, as those of the ilex or holm oak—may be entirely freed from the natural sap and converted at once into wood fit for use. In one hour entire tree-trunks receive an excellent and complete coloring. In fifteen minutes fir or beech railway-sleepers and in twenty-five minutes oak railway-sleepers may be impregnated with antiseptic substances. In equally-short periods whole trunks or even smaller sections of wood may be impregnated with fire-resisting substances, and thus made fireproof against the attack of the hottest fire.

The seasoning and coloring of the wood and also its treatment with antiseptic and fire-resisting substances may be undertaken with green wood without any previous drying or evaporating.

Having now described my invention, what I claim as new, and desire to secure by Letters Patent, is—

1. An apparatus for impregnating tree-trunks or wood longitudinally, consisting of a container *a* being closed at one end by a cover or door *l* provided with a number of pipes extending into bell-mouthing cutters 6 and at the other end by a cover or door *g* in combination with three partitions *j o s*, of which the center one *o* has a suitable number of cylinders for receiving pistons attached to pipes *t*, which pipes also extend into bell-mouthing cutters *u* and pass through the partitions *j* and *s* by means of stuffing-boxes, the said bell-mouthing cutters being adapted to penetrate the ends of the wood to be treated when a pressure medium is admitted to the middle chamber *q*, but being forced out of the wood on the admission of the pressure medium to the inner chamber *r* while from the outer chamber *p* situated between the door *g* and the partition *j* the impregnating fluid can be injected into the wood substantially as hereinbefore set forth.

2. In combination with the container, the bell-mouthing cutters, the conduits leading thereto, a cover carrying one set of said cutters, said cover comprising a chamber and being hinged to the container and a pipe leading to said chamber, substantially as described.

In witness whereof I have hereunto set my hand in presence of two witnesses.

GEORG FRIEDRICH LEBIODA.
